Primary Examiner — Richard Edgar*Assistant Examiner* — Jessica Ruth Grable(74) *Attorney, Agent, or Firm* — Thedford I. Hitaffer;
 Hitaffer & Hitaffer, PLLC(57) **CLAIM**

The ornamental design for a bed, as shown and described.

DESCRIPTION

FIG. 1 is a front perspective view of a bed.

FIG. 2 is a rear elevational view thereof.

FIG. 3 is a top plan view thereof.

FIG. 4 is a right side elevational view thereof.

FIG. 5 is a right perspective view thereof with a foot section extended.

FIG. 6 is a rear perspective view thereof with a foot section extended and with a foot panel for insertion in the extended foot section.

FIG. 7 is a top plan view of a base frame thereof.

FIG. 8 is a top plan view of an alternative base frame thereof; and,

FIG. 9 is a top plan view of another alternative base frame thereof.

The broken lines depict portions of the bed and form no part of the claimed design.
